UNITED STATES PATENT OFFICE.

FREDRICK HAITZ, OF TOWANDA, ILLINOIS.

UMBRELLA-SUPPORT.

SPECIFICATION forming part of Letters Patent No. 314,290, dated March 24, 1885.

Application filed January 14, 1885. (No model.)

To all whom it may concern:

Be it known that I, FREDRICK HAITZ, a citizen of the United States, residing at Towanda, in the county of McLean and State of Illinois, have invented a new and useful Improvement in Umbrella Attachments to Vehicles, of which the following is a specification, reference being had to the accompanying drawings.

10 My invention relates to an improvement in umbrella-supports; and it consists in the peculiar construction and combination of devices, that will be more fully set forth hereinafter, and particularly pointed out in the 15 claims.

15 The object of my invention is to provide an umbrella-support that is adapted to attach an umbrella to a wagon or other vehicle, or to an agricultural machine—such as a mowing-machine, a grain-binder, or corn-planter, &c.—said support being provided with means by which the umbrella may be adjusted vertically or horizontally, or inclined to any desired angle.

20 In the accompanying drawings, Figure 1 is a side elevation of my invention complete, showing an umbrella attached thereto. Fig. 2 is a similar view of my support, taken at right angles to Fig. 1, the umbrella being 25 omitted. Fig. 3 is a vertical central sectional view. Figs. 4 and 5 are detailed views.

30 Referring to the letters on the accompanying drawings, *a* represents a casting, which forms the means for the attachment of the support to the vehicle or machine. This casting or base is provided with a flange, *a'*, which extends horizontally from the upper edge of the casting on one side. This flange rests on the upper edge of the seat or body to which 35 the support is attached, and which I have indicated in dotted lines in Figs. 1 and 2, and a bolt, *a''*, is provided, which passes horizontally through the casting or base, and through the side of the seat or body. A nut, *a'''*, is applied to the threaded end of the bolt, and secures the base or casting rigidly in position. 40 From the upper side of the base extends the vertical hollow shaft *b*, which has slots *b'* cut in opposite sides near its upper end. A sleeve, 45 *c*, which is of a diameter corresponding to the interior diameter of the hollow shaft, is placed in said shaft, and is retained therein and per-

mitted a slight vertical play by a pin, *c'*, which passes through the slots *b'* and through the lower end of the sleeve. An extensible 55 spring, *d*, is placed in the shaft *b*, and bears against the lower end of the sleeve, and thereby prevents the sleeve from jarring and gives it an easy vertical play in the hollow shaft. The sleeve *c* has a slot, *c''*, cut on one side, 60 which slot extends nearly the length of the sleeve, and from one side of the slot, at a right angle thereto, are formed the curved indents *c'''*, which are preferably equidistant apart, and which extend the length of the slot. A sup- 65 porting-rod, *e*, which has a head, *f*, is located in the sleeve *c*, and is secured therein at any desired height by means of the sliding catch *f'*, which slides on a transverse pin, *f''*, that projects from one side of the rod near the bottom thereof. This catch is provided with a projecting stud, *f'''*, which when the catch is 70 pressed in on the pin enters the slot *c''* and partially turns the rod *e*, so as to cause the pin *f''* to enter one of the indents, and thereby support the rod in place. It will be very 75 readily understood that any desired vertical adjustment may thus be made for the supporting-rod.

Near the upper end of the rod *e* are cut 80 notches *e'*, one each on four sides, and through the head *f* extends horizontally a turning-pin, *g*, which is provided with a flattened projecting head, *g'*, and which has a notch, *g''*, which, when the upper end of the supporting-rod is 85 passed through the opening *f'''*, registers with one of the notches *e'* of said rod. A quarter-turn of the pin *g* causes it to enter one of the notches *e'*, and thus binds the head to the supporting-rod and prevents rotation thereon. 90 There being four of the notches *e'*, it is clear that the head may be secured to the rod at either of the four points of a circle. A washer, *e''*, bears against the under side of the head, and a washer, *e'''*, bears against the upper side 95 thereof, and is clamped thereto by a nut, *e'''*, which fits on the screw-threaded upper end of the rod.

h represents a horizontal rod, which is secured in a horizontal opening, *f''*, that is made 100 in the head, and is permitted rotation therein. A semicircular flange, *f'''*, depends from one end of the head, being drawn from the center of the opening *f''*, and this flange has a series

of indents, f^6 , formed in its outer face, near its edge, as shown. An arm, h' , projects from the rod h at right angles to said rod, and the lower end of this arm has a spring-actuated bolt, h^2 , which is adapted to enter either of the series of indents, and thereby secure the rod h at any desired point. The outer end of the rod h is squared on its upper side, as at h^3 , and on this end is fitted the enlarged supporting end or base k of the hollow shaft k' , that is adapted to receive the lower end of the umbrella-rod l . Notches h^4 are made on the upper side of the rod h , and a spring-actuated bolt, l' , similar to the bolt h^2 , engages with one of these notches, and thus secures the shaft k' to the rod h at any desired point. A slot, k^2 , is cut in the shaft k' , near its upper edge.

l represents an umbrella-rod, which is confined in position in the shaft k' by means of a spring-detent, m' , that enters the slot k^2 . This umbrella-rod is provided with a spring-detent, m^2 , near its upper end, and with a similar detent, m^3 , which is located near the detent m' , and near the lower end of the umbrella-rod.

n represents a thimble, which is provided with a slot, n' , for the reception of the detent m^2 , and has a flange, n^2 , projecting out from near its lower end. The lower end of this thimble n is supported in the upper end of a second thimble, o , and the umbrella-rod passes through both of these thimbles, as shown. A spring-actuated catch, o' , is pivoted to the thimble o , and engages with the flange n^2 of the thimble n , and thus secures said thimbles together. A slot, o^2 , that is cut in the thimble o , is for the detent m^3 when the umbrella-thimbles are at the lower end of the umbrella-rod. The ribs of the umbrella are pivoted to the upper end of the thimble n , as at n^3 , and the lower ends of the supporting-stays of the umbrella are pivoted to the thimble o , as at o^3 . Ears o^4 project upwardly from the upper end of the thimble o , and enter recesses n^4 , that are made in the flange n^2 of the thimble n , and thus prevents one of the thimbles from being rotated or turned independently of the other. These thimbles, with the cover, ribs, and stays of the umbrella, are adapted to slide up and down upon the umbrella-rod, or to be removed

entirely therefrom. When the thimbles are 50 locked together, the umbrella is open, and by pressing in the detent m^3 the umbrella can be removed from the rod and used independently of said rod, if desired.

An umbrella-support thus constructed can 55 be attached to any vehicle, and allows the umbrella to be adjusted vertically, horizontally, and to be swung around to any desired point of a circle, or to be inclined to any desired angle.

Having thus described my invention, I claim—

1. The combination of the base a , hollow shaft b , sleeve c , supporting-rod e , having head f , a catch for securing the rod to the sleeve at any desired point, horizontal rod h , journaled in the head f , and a catch for securing said rod at any desired point of rotation, and vertical hollow shaft k' , that is adapted to slide on rod h , and to receive and support an umbrella, substantially as described.

2. The combination of the base a , hollow shaft b , spring d , sleeve c , bearing on said spring, supporting-rod e , having head f , a catch for securing the rod to the sleeve at any desired point, horizontal rod h , journaled in the head, and a catch for securing said rod at any desired point of rotation, and vertical shaft k' , that is adapted to slide on rod h and to receive and support an umbrella, substantially as described.

3. The combination of the base a , having hollow shaft b , sleeve c , supporting-rod e , head f , swiveled to rod e , and a catch for clamping the head to the rod, horizontal rod h , journaled in the head, and a catch for securing said rod at any desired point of rotation, and vertical shaft k' , that is adapted to slide on rod h , and to receive and support an umbrella, substantially as described.

In testimony that I claim the foregoing as my own I have hereto affixed my signature in presence of two witnesses.

FREDRICK HAITZ.
